UNITED STATES PATENT OFFICE.

JOE GARLAND WEAVER, OF ACKERMAN, MISSISSIPPI.

MECHANICAL MOVEMENT.

Application filed April 2, 1923. Serial No. 629,348.

To all whom it may concern:

Be it known that I, JOE G. WEAVER, a citizen of the United States, residing at Ackerman, in the county of Choctaw and State of Mississippi, have invented certain new and useful Improvements in a Mechanical Movement, of which the following is a specification.

My invention relates to a mechanical movement, and has for its particular object the provision of a novel and improved mechanism adapted to be used in connection with power engines.

One object of the present invention is to provide a mechanism of this character in which an engine will be absolutely prevented from stopping on dead center.

A further object of the invention is to provide mechanism of this character which will generally add to the efficiency of an engine when used therewith.

With these general objects in view and such others as will be apparent from the description, the invention resides in the novel construction, combination, and arrangement of parts hereinafter described and claimed and illustrated in the accompanying drawings, in which—

Figure 1 is an elevation of an engine equipped with the invention;

Figure 2, a top plan view thereof;

Figure 3, a vertical elevation, partly in section, of the upper end of the main shaft;

Figure 4, a vertical section on the line 35 4—4 of Figure 1; and

Figure 5, a horizontal section taken through Figure 4.

The invention is shown as applied to an engine 1 having the usual piston 2 and fly wheel 3, which is mounted on a suitable elevated platform 4. Below the platform 4, and spaced appreciably therefrom, are arranged two horizontal parallel platforms 5 and 6, in the lowermost of which a shaft 7 is journaled in the socket bearing 8 at its lower end and through a slide bearing 9 at its upper end, the shaft being disposed vertically between the two platforms. The shaft 7 carries a pulley 10 over which a belt 11 is arranged in connection with the fly wheel

12 disposed on the power take-off shaft 13, which may be suitably mounted at any desired point.

At the upper end of the shaft 7 is disposed the universal joint 14 connected with a vertically arranged shaft 15 extending upwardly through the horizontal slot 16 arranged in the platform 4. At a point adjacent the bottom of the platform 4, shaft 15 is equipped with a weight 17 carried on the outer end of the bracket arms 18 connected at their inner ends with the shaft by any suitable manner of fastening so that the weight is rigidly secured to the shaft. The lowermost bracket arm 18 extends at right angles to the shaft whereby, when the shaft is in the vertical position, as illustrated in Figure 1, the weight 17 will be in its highest position, and any displacement of the shaft 15 from the vertical position will cause the weight to travel in a downward path.

The upper end of the shaft 15 is adapted to reciprocate in the slot 16, and is mounted therein in substantially semi-circular slide bearings 19 disposed in similarly formed grooves arranged in a guideway 20 mounted on the platform 4, or formed integrally therewith. Journalled on stub-shafts 21 received in the bearings 19, is a block 22 having a central bore through which the shaft 15 extends. The block 22 is provided with a race-way 23 in which ball bearings 24 are disposed to provide a bearing for rotation of the shaft within the block. A lever 25, provided at one end with a socket adapted to engage over the extreme upper end of the shaft 15, is rigidly secured to the shaft at this point by means of a set screw or other suitable fastening element 26 passed through a wall of the socket and engaged with the shaft. The lever extends laterally at a right angle from the shaft and is provided at its outer end with an integral upstanding ball 27 received in the ball bearing socket carried in the adjacent end of the lever arm 28 mounted by means of ball and socket connection on a standard 29 disposed in longitudinal alignment with the slot 16 on the platform 4 and spaced consid-

erably therefrom. The mounting of the lever arm 28 is such that in the vertical position of the shaft 15 the arm will assume the position in Figures 1 and 2, being arranged on a slight upward incline.

Between the guideway 20 and the lever 15, the shaft 25 is provided with a sleeve 30 rigidly secured thereto providing a bearing mounted on the collar 31 disposed thereover, which collar is pivotally connected by means of stub shafts 32 with the forked arms 33 disposed on the end of a longitudinally arranged lever 34 pivotally connected at its opposite end, as at 35, to a rocking arm 36 pivoted at its lower end on a shaft 37 journaled in the bearings 38 disposed on the platform 4 in longitudinal alignment with the slot 16. The lever 34 is connected to the rocking arm 36 at a point adjacent to its upper end, as illustrated in Figure 1. Between the extreme upper end of the rocking arm 36 and the fly wheel 3 of the engine is disposed a pitman 39 whereby on rotation of the fly wheel the arm 36 will be rocked in its bearings acting through the medium of the lever 34 to reciprocate the shaft 15 in the guide 20.

By reason of the mounting of the collar 31 and the rigid connection of the lever 25 with the upper end of the shaft 15, the shaft will, when reciprocated in the slot, be rotated through the medium of the ball and socket connection of the outer end of the lever 25 with the lever 28, which lever 35 will reciprocate in the arc of a circle, as best illustrated in Figure 2, and the rotation imparted to the shaft 15 will be transmitted through the medium of the universal joint 14 to the shaft 7 and from thence through the medium of a belt 11, over the pulley 10 and fly wheel 12 to the power take-up shaft 13. The arrangement of the weight 17 will impart an added momentum to the rotation of shaft 15, by reason of its mounting, as when the shaft is displaced from its vertical position, the weight will begin to travel in a downward path and will be sufficient to carry the engine beyond the dead center, as in normal position the weight will likewise come to rest at its lowermost point, as illustrated in Figure 1 in dotted lines.

While I have illustrated and described certain details entering into the construction and operation of the invention, I desire it to be understood that I do not intend to limit myself to these, but that any changes may be made in the structural details, and such modifications embodied as will fall within the scope of the invention as claimed.

I claim:

1. A device of the character described comprising vertically spaced supports, a shaft vertically disposed between said sup-

ports, one end of said shaft being adapted for horizontal reciprocation through one of said supports, power operated means for imparting reciprocation to said end of the shaft, means disposed on one of said supports for imparting rotation to said shaft during its reciprocatory movement, and power take-off means disposed on the other end of said shaft.

2. A device of the character described comprising vertically spaced supports, a shaft journaled between said supports, one portion of said shaft being adapted for horizontal reciprocation through one of said supports, power operated means carried by one of said supports for imparting horizontal reciprocation to said portion of the shaft, means carried by one of said supports for causing rotation of said shaft during reciprocatory movement thereof, means carried by said shaft for imparting momentum thereto in its rotation, and power take-off means disposed on one end of the shaft.

3. A device of the character described, comprising vertically spaced supports, a shaft vertically arranged in said supports, one portion of said shaft being vertically journaled in said supports, another portion of said shaft being adapted for horizontal reciprocation through one of said supports, bearings in said shaft to permit rotation of both portions thereof in said supports, power operated means for imparting horizontal reciprocation to one portion of the shaft, means carried by one of said supports for causing rotation of the shaft during reciprocatory movement thereof, means carried by the reciprocating portion of said shaft for imparting momentum thereto during its rotation, and a power take-off means disposed on one end of the shaft.

4. A device of the character described comprising a plurality of vertically spaced supports, a rotatable shaft vertically journaled between certain of said supports, a universal joint on the upper end of the said shaft, a second shaft connected with said first named shaft by means of said universal joint, said second shaft extending vertically through another of said supports, a guide arranged in said last named support for permitting horizontal reciprocation of said second shaft therein, power operated means carried by said last named support for imparting horizontal reciprocation to said second shaft, means disposed on said last named support for causing rotation of said second shaft during reciprocatory movement, and power take-off means carried by said first named shaft.

5. A device of the character described comprising a plurality of vertically spaced supports, a vertically disposed shaft rotatably journaled between certain of said supports, a second shaft adapted for horizon-

tal reciprocation through another of said supports, a universal joint connecting said shafts, power operated means carried by said last named support for imparting horizontal reciprocation to said second shaft, means for causing rotation of said second shaft during the reciprocatory movement thereof, means carried by said second shaft for imparting momentum thereto during rotation, and power take-off means carried by said vertically disposed shaft.

In testimony whereof I affix my signature.

JOE GARLAND WEAVER.
